CLAIM

The ornamental design for a wallet, as shown and described.

DESCRIPTION

FIG. 1 is a perspective view of a first embodiment of the invention in its closed position;

FIG. 2 is a front plan view thereof;

FIG. 3 is a back plan view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the invention in its open position;

FIG. 9 is an exterior view thereof;

FIG. 10 is an interior view thereof;

FIG. 11 is a top plan view thereof;

FIG. 12 is a bottom plan view thereof;

FIG. 13 is a left side elevation view thereof;

FIG. 14 is a right side elevation view thereof;

FIG. 15 is a perspective view of a second embodiment of the invention in its closed position;

FIG. 16 is a front plan view thereof;

FIG. 17 is a back plan view thereof;

FIG. 18 is a left side elevation view thereof;

FIG. 19 is a right side elevation view thereof;

FIG. 20 is a top plan view thereof;

FIG. 21 is a bottom plan view thereof;

FIG. 22 is a perspective view of the invention in its open position;

FIG. 23 is an exterior view thereof;

FIG. 24 is an interior view thereof;

FIG. 25 is a top plan view thereof;

FIG. 26 is a bottom plan view thereof;

FIG. 27 is a left side elevation view thereof; and,

FIG. 28 is a right side elevation view thereof.

The broken lines shown in the drawings are illustrative of environmental structure only and form no part of the claimed design
